AUBREY L. BROOMALL, OF WILKINSBURG, AND EDWIN G. TIDLUND, OF PITTSBURGH, PENNSYLVANIA, ASSIGNORS TO WESTINGHOUSE ELECTRIC AND MANUFACTURING COMPANY, A CORPORATION OF PENNSYLVANIA.

MOTOR STRUCTURE.

1,314,500.

Specification of Letters Patent. Patented Sept. 2, 1919.

Application filed October 9, 1914. Serial No. 865,844.

To all whom it may concern:

Be it known that we, AUBREY L. BROOMALL, a citizen of the United States, and a resident of Wilkinsburg, in the county of Allegheny, and State of Pennsylvania, and EDWIN G. TIDLUND, a subject of the King of Sweden, and a resident of Pittsburgh, in the county of Allegheny and State of Pennsylvania, have invented a new and useful Improvement in Motor Structures, of which the following is a specification.

Our invention relates to motor structures, and it has special reference to axle dust guards, such as are employed on railway motors for the purpose of preventing dust and dirt from working into the ends of the axle bearings.

One of the objects of our invention is to improve the structure of devices of the above-indicated character and to provide a device of light weight and rugged construction which shall perform its intended functions with reliability and which, moreover, shall permit a material reduction in the weight and cost of the associated motor.

Heretofore, it has been customary to provide the motor with an integral and more or less bulky flange which extended between the axle brackets, and to secure thereto a guard of sheet metal which is adapted to envelop the exposed portion of the axle between the axle seats. This construction involved excessive material, was bulky, and, moreover, required expensive machine work to insure a tight joint between the flange and the sheet metal guard.

According to our present invention, we propose to eliminate the above-mentioned flange and to provide a split tubular dust guard of sheet material which shall completely surround the axle between the side bearings and shall project slightly into the ends of the axle seats and be positioned thereby.

In the drawing, Figure 1 is a plan view of a portion of railway motor embodying our invention; Fig. 2 is a view, partially in section and partially in side elevation, of a portion of the apparatus shown in Fig. 1; and Fig. 3 is a view, partially in section and partially in end elevation, of our dust guard and its associated axle cap and bracket, the section being taken along the lines III—III of Fig. 2.

Referring to the drawing, the apparatus shown comprises a railway motor 1 having side bearings 2 and 3 for receiving an axle 4 which is enveloped by a dust guard 5 throughout that portion thereof which extends between the side bearings.

The motor 1 pertains only indirectly to our present invention, so far as its structural details are concerned, and, therefore, may be of any well-known construction.

The motor 1 has associated integrally therewith a plurality of side axle brackets 7 and 8 which are located at substantially the respective ends of the motor. Coöperating with these axle brackets 7 and 8 are detachable cap members 9 and 10 that are adapted to be bolted or otherwise rigidly secured thereto to form seats for bearing members or brasses 12 and 13. Within the coöperating parts 7, 8 and 9 and 10, which constitute the seats, the split bearing members 12 and 13 are disposed in accordance with the usual practice, and said bearing members 12 and 13 receive the axle 4 and provide suitable bearing surfaces therefor. The bearing members 12 and 13 are somewhat shorter in length than the axle caps and brackets of the axle seats and, hence, provide slight recesses or annular openings 15 at the inner ends thereof. These recesses 15 are adapted to receive the respective outer ends 16 of the tubular dust guard 5, which surrounds the axle 4 between the bearings 2 and 3 and is interposed between the inner ends of the respective bearing members 12 and 13. The inner ends of the integral axle brackets 7 and 8 are provided with diametrically opposite and inwardly projecting lugs 18 and 19 for a purpose to be hereinafter set forth.

The dust guard 5 comprises a pair of semi-cylindrical sheet metal members 20 and 21, the longitudinal edges of which are placed in abutting relation and are maintained in position preferably by means of strips 23 and 24 which overlap the joints and are spot-welded to the half 21 of the dust guard, or are otherwise suitably fastened thereto. The respective ends of the strips 23 and 24 are provided with notches 25 for the purpose of receiving the axle bracket lugs 18 and 19 whereby the tubular dust guard 5 is restrained against turning.

Assuming the detachable axle caps 9 and

10 and the bearing members 12 and 13 to be removed and the motor 1 to be positioned upon the axle 4, the assembly of parts is as follows: The dust guard member 21, with 5 its associated strips 23 and 24, is first disposed around the inner portion of the axle 4, with its respective ends 16 located in the recesses 15 of the axle brackets 7 and 8, after which the rear halves of the split bearing 10 members 12 and 13 are put in place. The other half of the dust guard member 20 and the remaining halves of the split bearing members 12 and 13 are then positioned, and the detachable axle caps 9 and 10 are assembled and rigidly clamped to the integral axle brackets 7 and 8 by suitable bolts.

Variations in the structural details and arrangement and location of parts may be effected without departing from the spirit 20 and scope of our invention. We, therefore, desire that only such limitations shall be imposed as are indicated in the appended claims.

We claim as our invention:

- 25 1. In a dynamo-electric machine, the combination with a frame having side axle bearings associated therewith, and an axle disposed in said bearings, of a tubular guard of sheet material surrounding said axle between 30 said bearings, and means coöperating with said bearings for restraining said guard from turning.
- 35 2. In a dynamo-electric machine, the combination with a frame having side axle bearings associated therewith, and an axle disposed in said bearings, of a guard of sheet material entirely inclosing said axle between 40 said bearings and restrained from turning by said bearings.
- 45 3. In a dynamo-electric machine, the combination with a frame having side axle bearings associated therewith, and an axle disposed in said bearings, of a tubular guard of sheet material enveloping said axle between 50 said bearings and having its respective ends in coöoperative engagement with said bearings and restrained from turning relative thereto.
- 55 4. In a dynamo-electric machine, the combination with a frame having alined axle seats and projections thereon, bearing mem-

bers within said seats, and an axle disposed in said bearing members, of a tubular guard surrounding said axle and interposed between said axle bearing members and having its respective ends positioned within said axle seats, and means on said guard coöperating with said axle seat projections whereby said guard is prevented from turning.

5. In a dynamo-electric machine, the combination with a frame having alined split axle seats, bearing members within said seats, and an axle disposed in said bearing members, of a tubular dust guard surrounding said axle and having its respective ends projecting slightly into the ends of said axle seats, and means associated with said guard and coöperating with said axle seats for preventing turning movements thereof.

6. In a dynamo-electric machine, the combination with a plurality of bearings and an axle disposed within said bearings, of a split tubular member surrounding said axle and extending between adjacent bearings, and means overlapping the abutting edges of the said split member.

7. In a dynamo-electric machine, the combination with a frame having side axle bearings, and an axle disposed within said bearings, of a split tubular guard surrounding said axle between said bearings, side strips overlapping the edges of said guard and secured to one portion thereof, and means associated with said side strips for restraining the turning of said guard.

8. In a dynamo-electric machine, the combination with a frame having side axle bearings, and an axle disposed within said bearings, of a split tubular guard surrounding 90 said axle between said bearings, and side strips overlapping the edges of said guard and secured to one portion thereof.

In testimony whereof, we have hereunto subscribed our names this 7th day of Oct., 95 1914.

AUBREY L. BROOMALL.
EDWIN G. TIDLUND.
